LUMINESCENT TUBE

Arthur Stephen Ford, Philmont, N. Y., assignor
to General Electric Vapor Lamp Co., Hoboken,
N. J., a corporation of New Jersey

Application May 31, 1928, Serial No. 281,989

1 Claim. (Cl. 176—122)

This invention relates to illuminating tubes of the neon type, and I will describe it with reference to the accompanying drawings:

Fig. 1 shows a sectional view of one form of my improved lamp in which an outer container 1 preferably of glass is exhausted of air and filled with neon or other suitable gas after which the glass container is hermetically sealed at its base 2 by means familiar to those skilled in the art. The 5 container is provided with a central rod or support 3, preferably a glass tube, and this rod or tube is provided with baffle plates 4 and 5 at the lower and upper extremity respectively to serve a purpose which will be described later.

10 This central rod or tube also serves as a support for the two electrodes 6 and 7 which are disposed as shown in relation to the baffle plates 4 and 5 and which can be of any suitable material or shape. Lead in wires 8 and 9 passing through the base of the container serve to convey the electric current to the two electrodes 6 and 7, the former being preferably disposed around the central rod under the baffle plate 4 and the second electrode 7 being disposed at the top of the 15 central rod or tube and above the baffle plate 5, the lead in wire for the upper electrode being carried up through the center of the glass tube 3 as shown. The baffle plates 4 and 5 can be of glass and integral with the rod or support 3 or can 20 be made of any other suitable material such as sheet mica and separably attached to the central rod.

25 When the electrodes of such a gas filled lamp are excited by a suitable current, the current passes to and from the electrodes through the gas with which the lamp is filled exciting the particles of such gas into luminosity. In the absence of the baffle plates 4 and 5 the current would take the shortest path through such gas and would 30 result in a luminous column of gas around the central rod but at some distance from the outer wall of the glass container. The presence of the baffle plates prevents this as the current is deflected laterally and away from the central rod 35 and establishes a path adjacent to the inner surface of the lamp container as shown by the arrows in the drawings which indicate the path taken by the exciting current from the upper electrode to the lower electrode.

40 This results in greater diameter to the mass of glowing gas with greater accompanying illumination and militates against overheating the electrodes and the central lead in wire as well as preventing conduction losses through the glass central tube to the said lead in wire.

These baffle plates as shown in Fig. 1 are of such dimensions that they can be mounted on the central support 3 and inserted in the lamp container through the opening at the neck of the container before it is exhausted and sealed but these baffle plates may be of greater dimensions if desired and the outer container may be blown or fashioned in two parts, that is, a lower cup A in which the central rod may be disposed and the lead in wires and electrodes mounted and a second upper dome shaped cover B may be then superposed. Both this lower cup and upper dome may be provided with a turned lip or rim at the point of juncture and these rims or lips can be cemented, melted, or welded together in any suitable or convenient manner in which case the joint will be established at the point 10 as shown in Fig. 1 or at any other convenient location.

45 Fig. 2 shows a modified form of one of my lamps in which the use of baffle plates is omitted, the path of the exciting current through the gas being controlled by the interposition of a second internal container 11 which supports the central rod 3 and the electrodes 6 and 7. The electrode 6 at the base is shown in ring form shape, the gas chamber proper being the area between the internal container 11 and the outer casing 1.

50 When the electrodes of such a lamp are excited the luminous gas is confined to the said outside area lying under the outer case and the luminous area is confined to such gas as is contained therein. The internal chamber 11 may be exhausted of air and sealed from the luminous gas or may be exhausted of air and filled with the luminous gas which is provided with means of access to the excited area through apertures 12 or the internal chamber may be filled with air and hermetically sealed from the gas area proper.

55 Fig. 3 shows yet another form of lamp designed to control the area of the luminous gas in which the baffle plates as shown in Fig. 1 are dispensed with and an internal chamber 11 is employed to control and secure a brush like discharge through the luminous gas from one electrode to the other.

The internal chamber 11 in this form of lamp 45 is blown or fashioned with vertical depressions extending from top to bottom and this internal chamber is so constructed as to nest snugly within the outer casing 1. The internal chamber is suitably mounted and sealed in the outer case as shown, and provided with electrodes 6 and 7 connected by lead in wires 8 and 9. The gas area proper is provided by the vertical spaces left in the vertical depressions fashioned on the surface of the internal chamber and the electric current 50

passing between the electrodes 6 and 7 has to pass through the gas in such vertical depressions exciting it to luminescence.

The internal chamber can be air filled, gas 5 filled, or exhausted of air and gas as may be desired.

The construction of this form of lamp will be more clearly understood by reference to Fig. 4 which represents a top view of the lamp on a line 10 4—4 as marked in Fig. 3. 11 is the internal chamber which fits snugly in the outer case 1. Vertical depressions 13 are radially disposed around the outer skin of the internal chamber 11, these depressions extending from the base 13' 15 (Fig. 3) to the top of said internal chamber 14 (Fig. 3). While the drawings show these gas filled depressions which control the path of the luminous gas as vertical, I do not wish to confine myself to vertical depressions only, as it is obvious 20 that they may be arranged spirally around the outer skin of the internal chamber 11 or they may be given any other form without departing from the essential principle of this part of my invention which is to provide a definite restricted 25 path for the luminous gas as near to the inside skin of the outside container as possible.

Similarly while the internal chamber 11 is described as made of clear glass, it may be made of opal or colored glass, may be silvered inside or 30 out, or decorated in any desired manner or made of any other suitable material.

Fig. 5 shows another form of lamp made according to my invention, the object of this form being to afford a multiplicity of colors or light 35 effects from a single lamp. The figure shows three tubes of glass or suitable translucent material 15, 16, 17 respectively, each furnished with individual electrodes 18, 19, 20 and 21, 22, 23. In practice individual lead in wires can be led to each 40 electrode as shown at 24, 25, 26, each being led through the walls of the glass tubes through properly insulated tubes preferably of glass, or I can provide a lead in wire common to all electrodes as shown at 27 where the lead in wire is 45 common to all electrodes and passes through the several light tubes. These three tubes 15, 16 and 17 can be of white glass or material or colored glass or material and the gases with which they are filled can be different or identical.

50 Inasmuch as the various noble gases such as argon, krypton, helium and neon each glow with a different characteristic color under the influence of the electric current, it follows that according to the gas which is so electrically excited 55 the color emitted from the lamp will differ.

If the glass or other material from which the tubes are constructed is clear and white then the gases which are invisible when inert will not affect the color of the gas which is excited and as each 60 different pair of electrodes are connected with the source of electricity the gas excited will afford its own distinct color without any interference from the other gases which are adjacent.

However more than one set of electrodes may 65 be connected simultaneously and a blended color may be secured from a lamp, for instance, if a gas giving a blue light is excited and at the same time a gas giving a yellow light is excited, the 70 resulting color of the light will be a blend of yellow and blue, namely a green. Again instead of a simple gas being provided in each tube respectively, a blend or mixture of gases can be pumped into any or all of the tubes and by variations of this nature practically any color or

colors of the spectrum can be secured from a single lamp.

Similarly the glass or other translucent material from which the tubes are constructed can be varied in color to affect as desired the resulting color of the light passing through them.

In Fig. 6 the arrangement shows three gas chambers 28, 29 and 30 arranged concentrically and provided with their individual electrodes 31, 32 and 33 and 34, 35 and 36, the former group 10 having their own individual lead in wires 37, 38 and 39 and the latter or upper group having a common lead in wire 40.

Figs. 7 and 8 show one form of arrangement of a group of lamps of the nature before described. Five lamps 41, 42, 43, 44 and 45 are disposed around a central reflecting chamber 46 (Fig. 8) and provided with a reflecting cowl 47 above which a transformer 48 can be attached. A pull chain 49 serves to actuate a switch. The 20 reflecting chamber 46 can be gas filled to serve as a source of light either in its entirety or it may be partially masked and partially open to direct its light in any desired direction. For instance, if the sides and top of such reflecting 25 lamp chamber are masked or silvered it will serve as a top and lateral reflector, while if the bottom of said lamp chamber is left free to the passage of the light from the luminous gas within it, then a downward spot light will be secured. 30 Similarly the reflecting lamp chamber can be of any desired color to afford a different character of light from that afforded by the lamps surrounding it.

Figs. 9-15 show details of light exciting gas 35 filled units designed to be combined for a multitude of desired effects. In these figures 50 represents a gas chamber of glass or other suitable translucent material as will be more clearly understood from reference to Fig. 12. This unit 40 is segmental in nature and is designed to be arranged radially with other similar gas chambers as shown in Fig. 9. Central leads 50' connect the electrodes 51 arranged in each chamber and strip electrodes 52 are arranged at the 45 outer periphery of the inside base plates of said chambers, said electrodes being suitably connected to the exciting current.

The arrangement is more clearly shown in Fig. 10 where the chambers 49 are provided with 50 central electrodes 51 and base strip electrodes 52.

The object of this form of lamp is to provide a circular plane lighting lamp suitable for hanging or attaching to the ceiling and designed to 55 throw a soft and diffused light downwards; to assist this effect the upper planes of the gas chambers can be made of opal or green glass or silvered or provided with any other suitable reflecting coating to prevent the upward escape of 60 the light.

In Fig. 11 instead of unit construction the circular lighting plan is shown as an integral chamber with container 50^a, upper electrode 51^a and lower electrode 52^a.

In Fig. 14 the gas container is shown in two parts, an upper cover 50^b and a base 53. The electrodes are shown as a conical central upper electrode 51^b and a lower ring electrode 52^b. The container after being filled with electrodes 70 and lead in wires is brought together with the base plate and the edges are cemented, welded, or melted together so as to make an air-tight joint and the container after being exhausted of air and filled with gas is sealed hermetically. 75

In Fig. 13 the container 50^c is arranged over a base plate 53^c which is joined to it by an hermetically sealed joint at its outer edge. A central electrode 51^c and a lower ring electrode 52^c is fixed in place and spacers or supports 54, preferably of glass, are fixed in place between the upper wall of the container and the base. The object of these supports is to prevent the deflection of the walls of the container during the process of manufacture when the air is being exhausted or the gas is being introduced.

Fig. 16 shows a modification of my invention intended to provide a lamp suitable for projecting a beam of light in any desired direction. In the drawings an outer shell or cover 55 of any suitable material is provided with a peripheral rim 56 to hold a front cover or lens 59. The gas chamber 58 is made of two concentric dishes of glass or other suitable material, preferably parabolic in contour, which are arranged to hold the exciting gas between them when their outer peripheral edges have been hermetically sealed at 59. Suitable electrodes 60 and 61 are connected by the lead in wires 62 and 63 to a transformer 64 which is, in turn, connected to the source of electrical supply. The back plate of the gas container can be silvered or provided with any suitable reflecting surface or cover to throw the light forward and the luminous gas fills the parabolic gas chamber and results in a beam of light being projected forward due to the contour of the gas chamber. When a lamp of such construction is used, for instance, as an automobile head light, it has the advantage of affording an intense beam of light which due to the absence of any internal filament is devoid of blinding glare as a person can gaze directly into the area of the light emitting unit without being blinded by its glare. Again it is a well known fact that the light emitted from luminous neon gas particularly has the power of penetrating mist or fog to a degree unequalled by any other illuminant and when this gas is excited in a parabolic gas chamber such as hereinafter illustrated, a source of light is provided which is particularly applicable to land, marine, or air signalling or illumination.

Figs. 17 and 18 show modifications of such a lamp especially applicable to lamps of large power and size. In these figures the parabolic gas chamber instead of being constructed of two integral glass dishes is built up of gas filled units similar in shape to that shown in Fig. 18. This gas container 65 is segmental in shape and when filled with gas and provided with electrodes and proper lead in connections is arranged radially as shown in Fig. 17 which is a part section of the front view of such a light projector. Here the gas filled units 65 are shown radially disposed in a projecting outer shell 55 which bears retaining lip 56 and cover glass or lens 57, although in practice I may omit the cover glass altogether in lamps of any considerable size, as the glass gas containers themselves serve to project the light forward without the aid of a front lens.

Figs. 19-23 illustrate modifications of my invention designed more particularly for the manufacture of advertising letters, signs and the like and show methods of manufacture and sign products that have many important advantages. It is well known that luminous gas letters of the ordinary type are made from glass tubing which is heated and bent into any desired shape to form the letter or phrase desired. This method of manufacture is slow, expensive, and inadequate

and the object of the methods and products illustrated in Figs. 19 to 23 is to eliminate these objections and provide a more artistic and useful product. To effect this result I build my advertising letters or signs on a luminous gas filled plate either square in shape as shown in Fig. 19 or circular in shape as shown in Fig. 20, although it is obvious that a rectangular or other desired shape can be adopted. The process of manufacture is as follows:—A tray 66 (Fig. 19) is made of glass or other suitable translucent material and is either blown or pressed in a mould or fabricated by any other convenient method known to those skilled in the art. This tray is provided with raised internal ribs 66^a and an outside retaining rim 66^b. These ribs do not entirely traverse the inside area of the tray being broken away alternately at the beginning and end as shown at 66^c where the retaining rim has been broken away to show the method of construction more clearly. It will be evident from the drawings that a continuous path is thus provided by the depression between the ribs starting from one corner of the tray 66^d to the far corner 66^e and when the two electrodes 66^f and 66^g are installed in place a cover plate of glass or like material 67 is placed over such tray and when softened by heat is welded at its joints to the outside rim of the tray and to the upper flattened edges of the ribs which traverse the tray proper. A suitable aperture is left for the tray to be exhausted of air and filled with the desired gas for illumination and after this is done and the tray hermetically sealed the passage of the electric current from one electrode to the other is confined to the gas filled tubular path provided between the ribs described and the gas filled plate glows in the same way as a plate made from lengths of closely bent glass tubing. It is obvious that the glass tray or its cover can be of any desired area, depth, contour, color or finish and the upper or cover plate can be imprinted or decorated in any desired design without departing from the principle of my invention.

Fig. 20 shows a similar construction applied to a circular plate or tray in which the tray 66 is provided with a continuous spirally disposed and raised fin or rib 66^a and electrodes 66^f and 66^g.

Fig. 21 shows a decorated cover plate which has been cemented or welded over a circular plate such as I have described and serves to indicate the wide range of artistic effects that can be obtained by this method of manufacture.

Figs. 22 and 23 illustrate practical methods of utilizing luminous plates such as I have described. 68 shows a luminous plate of square design as applied to a base plate 68' which serves as a background and support for a letter sign. In this part of the figure the front cover plate has been omitted in order to reveal the construction more clearly. 69 shows the luminous plate covered with a front blank cover of suitable material while 70 shows the addition of a front plate decorated with a letter I. This letter may be imprinted or superposed on the front plate in any suitable manner either in one color as shown in 70 or in a plurality of colors as shown in 71 where the cover plate 72 can be of one color, the letter can be of another color while a border around the letter 73 can be yet another color. Thus by a selection of color in the excited gas in the luminous plate itself and the addition of a color decorated front cover or second plate placed in front of such luminous plate cover practically 75

any colored effect can be secured. Similarly the luminous cover or the plate placed in front of such luminous cover can be provided with a decorated border design as shown at 14 and decorated corners or other devices such as are shown at 15 can be provided. By this method of manufacture it is obvious that each luminous signal can be filled with a different gas capable of giving a separate color when excited and these can be carried in stock by the manufacturer and will serve to form a unit or letter in any desired sign or device, all that is necessary being to slip in front of such a gas filled square the desired letter plate which may also be carried in stock. Again the sign can be changed at will by simply removing the front cover plate and the luminous square is protected at all times from the weather by the front plate. A number of other advantages and economies will occur to those familiar with the art.

Figs. 24-29 illustrate a modified method of construction whereby hollow letters of glass or other translucent material are pressed, blown, or moulded from sheets of the raw material. In Fig. 24 the plates 16-16 are impressed with the letter F. 17 one half of such letter substantially being fashioned from each plate so it appears in half relief as shown at 17 in Fig. 25. The two plates are placed together and cemented or welded together at all joints so as to provide an hermetically sealed container for the gas which it is desired to use after the electrodes have been suitably disposed within it. The excess material surrounding the letter may be left as shown in Fig. 25 or removed as shown in Fig. 26, but in either event a hollow tubular letter is provided which when fitted with electrodes and filled with neon gas or the like can be used for advertising or other purposes.

Fig. 27 shows a letter of substantially square or block design and here again vari-colored effects may be secured by using colored glass of different hues or decorating the sides of the letters with suitable colored designs. In Fig. 27 the excess material left when the two parts of the letter are brought together has been removed, but in Fig. 28 the excess material has been left in part in the shape of a fin or rib 18 and this fin or rib can be colored or decorated to give a contrasting effect from the body of the letter.

Fig. 29 is a side elevation of the letter shown in Fig. 28 showing the extending fin or rib 18.

Figs. 30 and 31 illustrate a new and simple means of manufacturing small luminous gas units in which a tube of glass or similar translucent material 19 is exhausted of air, filled with gas, provided with electrodes, and hermetically sealed in the usual way. The lettering of the sign is accomplished by the use of attachable letters 20 made of any suitable material and of any desired color or colors. These letters are placed in the desired position and cemented or welded into position outside the gas filled tube till they spell out the word or phrase desired as shown in Fig. 31. An outside casing 21 can be placed around the luminous tube for protective purposes and a transformer 22 can be attached to the tube with a lead in wire 23 which serves to connect the unit to the source of electric supply. It is obvious that the tube can be provided with a front plate bearing the letters in relief or imprinted or attached to same in any suitable manner without departing from the principle of my invention and again any suitable reflecting sur-

face can be placed at the rear of said tube to enhance the brilliance of the lighted tube.

Figs. 32, 33 and 34 show details of the internal construction of gas filled letters made according to my invention and illustrate the use of auxiliary deflecting internal partitions to control the course of the illuminated gas from electrode to electrode. In the illustrations the letters 24 have internal partitions 25 disposed according to the needs of each respective letter.

In Fig. 32 the electrodes 26 excite the gas which follows the path as indicated by the arrows in the illustration. It is obvious that without these partitions 25 the current would seek the shortest path from electrode to electrode without illuminating the whole letter, but by the use of these partitions the current is compelled to traverse the full length of the letter thus illuminating the entire area.

In Fig. 33 no internal partitions are employed, the current being free to follow its own path from electrode to electrode and as the path around the top half of the letter and the bottom half of the letter is identical in length and resistance, an equal illumination is secured.

In Fig. 34 the electric current can follow either of several paths from one electrode to another, but all of these paths present equal resistance and in no event can any portion of the letter remain unilluminated.

Figs. 35, 36, 37, 38, 39 and 40 relate to improvements in electrodes for use in luminous gas filled lamps. In Fig. 35 the electrode consists of a tube 27 preferably of glass provided with a lead in connection 28 which is in intimate electrical contact with a metallic or conducting lining 29 in the tube 27. This conducting lining may be an electrically deposited metallic coating or a sheet or tube of metallic foil. A hollow conducting electrode is thus provided through which the excited gas can circulate.

Figs. 37 and 38 show an electrode made from a spirally coiled wire of suitable material, the coil 30 as shown in detail in Fig. 38 is inserted in the tube 27 as shown in Fig. 37, but is shielded from actual contact with the gas to be excited by an inner lining 31, preferably of glass. The electrode chamber thus formed can either be filled with air or preferably the air is exhausted from said chamber through the air vent which is subsequently sealed in the usual manner. The object of enclosing the actual electrode surface away from contact with the gas to be illuminated is as follows. It is a well known fact that the luminous qualities of lamps of this character decrease sharply after a few months of use and this I find is principally due to the pollution of the gas itself from particles of the electrode metal which are thrown off due to the influence of the high potential current employed. By totally enclosing the electrode as shown, the energizing current is of sufficient intensity to act through the thin glass wall of the enclosing secondary tube and thus illuminate the gas with which the lamp is filled, but any particles thrown off or torn off by the pulsations of the current are prevented from having access to the gas itself and pollution and deterioration of the latter is thus prevented and the life of the lamp is greatly prolonged and the purity of its color maintained.

Figs. 36 and 39 show a form of electrode in which a suitable metallic or conducting powder is employed with a view of affording the maximum emitting surface in the most compact form.

In Fig. 36 the outer tube 27b is preferably pro-

vided with an inner metallic coating 93 and a front sealed wall 94. After the tube has been filled with the suitable powder electrode 95 it is exhausted of air through vent 92 and hermetically sealed. 96 shows a metallic electrode lead in designed to establish perfect contact with the metallic powder which in turn is in intimate contact with the metallic skin or cover 93 lying in close contact with the glass container 87 through which the energy passes to the gas in the lamp chamber.

In Fig. 39 the construction is similar with the exception that the conducting powder electrode is disposed in the container 87^c and around an internal tube 97 which permits the gas charge of the lamp to have access to the powdered electrode through the glass wall 98 inside the electrode as well as through the outer glass wall of the container 87^c.

Fig. 40 shows a means of modifying or controlling the color emitted by the gas with which the lamp may be filled. The container 87^a is filled with suitable electrodes 96^a exhausted of air and filled with neon or other similar gas. Before the container is sealed however a quantity of powder 97^a of impalpable fineness is introduced into the lamp which is then sealed in the usual way. Under the influence of the electric current the impalpable particles of powder become diffused throughout the gas with which the lamp is filled and modify the light emitted by the excited gas according to the nature of the powder. The powder selected can be of any desired constitution but is preferably of a non-oxidizable inert nature which involves no chemical reaction with the gas in the lamp although for special purposes I may elect to use a powder having a definite reaction with the gas in the lamp where modifications of intensity, diffusion or actinic values are desired.

Figs. 41 and 42 show details of an improved transformer or "booster" designed to operate on an electric circuit of comparatively low voltage and transform or "step up" said voltage to the high potential commonly used in luminous gas lamps of this nature. This transformer shown is designed to operate by plugging into the usual 110 volt house current and combines a plug for that purpose, transformer primary and secondary coils, a safety switch of novel design, and a socket to receive the lamp filled with neon gas or the like.

In Fig. 42 a shell or housing 99 holds the primary and secondary coils and is provided at its lower extremity with the screw socket contact piece 99^a designed to screw into the house socket. At the upper extremity is a socket 100 with bayonet joint 101 designed to receive the base of the lamp filled with neon or like gas (104, Fig. 41). A rotatable pointer 102 moves over the gauge 43 and indicates the intensity of the alteration which is being excited by the transformer.

Fig. 41 shows details of internal construction of my improved transforming socket and plug in which the housing 99 bears the coils 105 and 106 which are attached to the leads 107 and 108. At the top of these coils are arranged the double contact pieces 109, 110, which are so coupled to the transformer coils that the passage of the current is interrupted by the gap which exists between the two poles of each spring contact pair until the lamp 104 is screwed tightly in place.

The object of this construction is to avoid dangerous sparking between terminals carrying high

potential current for it is obvious if the 110 v. circuit which enters through the base socket 99^a were permitted free access through the transformer coils to the terminals in the upper socket 100 the poles in the latter bearing a current of many thousands of volts would spark and provide a source of danger from fire and unpleasant shock to any person accidentally touching them even while the low amperage would obviate the possibility of any serious injury. The operation of my improved socket as shown prevents any possibility of this as the action of the spring contact pieces in the upper socket precludes the possibility of any current between them until the lamp 104 is securely in place and contact of both poles of the lamp has been thoroughly established. In practice the socket is insulated from the source of current (such as the house circuit) and "dead" until the lamp 104 is screwed into position. As the base of lamp 104 descends into the screw socket (or bayonet joint as shown in Fig. 42) it first establishes its own contacts with the lines from the transformer coils but as the latter are not yet energized from the house circuit no possibility of sparking exists. The last movement downwards of the lamp 104 in the socket 100 however depresses the spring contacts 110, 110 into electrical contact which permits the house current to enter the coils and energize them but as the poles of the lamp 104 are already firmly in contact with the high potential terminals of the coil no sparking or unpleasant electric effects are possible. The use of such a compact safety transformer plug permits a much wider use of luminous gas lamps than before as no main transformer is needed on the circuit and a lamp filled with neon gas or the like can be easily and safety attached into any ordinary 110 v. socket provided this transforming plug is interposed between it and the lamp.

Fig. 43 shows an adaptation of some of the constructive details I have described to a notice or bulletin board suitable for advertising or other purposes. A vertical hollow gas filled tray 111 is furnished with internal ribs 112 and covered with a cover 113 preferably of frosted, ground or opal glass. The tray itself is gas filled, provided with electrodes, 114 and on passage of the electric current along the depressions provided by the internal ribs, glows with lights as I have already described in relation to Figs. 19 and 22. This tray or hollow plate lamp is mounted on a suitable support 115 with which one or more transformers 116 can be incorporated. When employed as a notice or bulletin board any desired message may be printed or written on the covering glass in front of the lamp and an actual piece of merchandise such as the cigar 117 can be temporarily fastened on the said cover. When it is desired to change the message on the board the merchandise is removed and the writing wiped off or otherwise obliterated and a fresh message substituted.

Figs. 44 and 45 illustrate a method of manufacturing hermetically sealed glass containers from glass moulded forms.

Fig. 44 shows in section upper and lower glass tray like blanks which it is desired to seal at their overlapping edges.

The lower tray 118, Fig. 45, is covered with the top tray 119 both made of glass or other suitable material. A cover of suitable material 121 is then placed above it and held firmly in place by any suitable means. Compressed air is introduced between the upper and lower plate through the

glass, air pipe 122 which enters the base of the lower glass plate at 123 being introduced by heating and perforating the lower plate in a manner well understood by those skilled in the glass blower's art. Heat is applied to the lower mould by means of a gas main 124 from which the flames or heated air 125 issue and play over the surface of the lower mould. The glass containers inside the mould become softened with the heat till the 10 side walls which overlap are sufficiently melted to weld together under the pressure of the air which is forced through the air pipe 122. After this has been accomplished the mould and contents is allowed to cool till the welded glass container can be removed from the air inside is exhausted and any desired gas introduced through the air pipe 122 which is then sealed and cut off close to the surface of the lower part of the container. In the illustration shown by Figs. 44 and 15 20 45 the glass moulded blanks have already been provided with the side walls by a previous moulding operation, but it is obvious that this part of the process of manufacture can be combined with the sealing operation and the sheets of glass from 25 which the upper and lower part of the container are to be formed can be introduced into a mould substantially as shown in Fig. 45, and after heating the side walls of the containers can be first shaped by pressure and the sealing operation can 30 follow as before described.

Figs. 46 and 47 illustrate a modification of my invention as applied to a conventional sign for barbers. A central supporting frame 126 bears one or more spirally wound glass tubes 127, 128 35 and 129, each tube being filled with a gas which upon being electrically excited will glow with red, white and blue light respectively. A small transformer can be housed in the lower part of the frame 126 from which the lead 130 emerges to 40 connect with the source of electric supply.

Fig. 47 shows a modification in which a glass tube 131, preferably of square section, is imprinted or covered with plates of red, white and blue color as shown and mounted in a frame 132, the base 45 of which bears a transformer 133. The glass tube is fitted with electrodes and filled with a luminous gas, thus constituting a lamp, and the

decorated and colored panels on the sides identify it as a barber's sign.

Figs. 48, 49 and 50 show the adaptation of a luminous gas lamp as hereinbefore described, to a dummy head for barber's display indicating an appeal for feminine patronage. 5

In Fig. 48 a hollow blown or moulded head 134 is gas filled, and fitted with suitable electrodes and supported by a base 135 covered by a projecting glass cover 136. When the current is turned on the interior of the head glows with light affording a brilliant advertising sign. 10

Fig. 49 shows a base 135 supporting a hollow gas filled lamp 136 on one or more faces of which is imprinted a female head to serve the purposes before described, while Fig. 50 shows still another modification in which a double faced moulded head, preferably of glass, and suitably decorated, is gas filled and provided with electrodes to serve as a barber's sign. 15

Fig. 51 is a modification of the multi-color lamp described in Figs. 5 and 6, but is more particularly designed for projection purposes. In this form a plurality of lens like chambers 137, 138 and 139 are placed one in front of the other 20 and each provided with a pair of electrodes 140—140—140. These chambers are exhausted of air, gas filled with the desired gas, and provided with suitable lead in wires in the usual manner. 25

If preferred the rear gas chamber can be sil- 30 vered on its back for reflecting purposes or the series of chambers can be mounted in a suitable frame bearing a reflector at its back.

It will be obvious that by selectively exciting 35 the different color gases with which the several chambers are filled, a variety of color beams can be directed forward from such a projector.

I claim:

An electric gaseous discharge device comprising 40 a sealed envelope containing a gaseous atmosphere, electrodes sealed within said envelope and means to direct a gaseous discharge into a plurality of paths along the surface of said envelope, said means comprising a concentric inner member 45 having ridges in contact with said surface.

ARTHUR S. FORD.
